Primary Examiner — Rhea Shields*(74) Attorney, Agent, or Firm* — Dickinson Wright PLLC(57) **CLAIM**

The ornamental design for a portable adapter, as shown and described.

DESCRIPTION

1.-2. Portable adapter

1.1 : Front

1.2 : Back

1.3 : Left

1.4 : Right

1.5 : Top

1.6 : Perspective

1.7 : Perspective

2.1 Perspective

1.1 is a front elevation view of a portable adapter (dual mode) showing our new design; 1.2 is a back elevation view thereof; 1.3 is a left side elevation view thereof; 1.4 is a right side elevation view thereof; 1.5 is a top plan view thereof; 1.6 is a perspective view thereof; 1.7 is another perspective view thereof; 2. 2.1 is a perspective view of a portable adapter (dual mode) showing our new design.

The broken lines in Figures 1.1-2.1 depict portions of the portable adapter that form no part of the claimed design.

1 Claim, 8 Drawing Sheets(56)
